UNITED STATES PATENT OFFICE.

ROBERT H. F. SEWALL, OF NEW ORLEANS, LOUISIANA.

CATTLE-GUARD.

1,060,713.

Specification of Letters Patent.

Patented May 6, 1913.

Application filed May 2, 1912. Serial No. 694,772.

To all whom it may concern:

Be it known that I, ROBERT H. F. SEWALL, a citizen of the United States, residing at New Orleans, in the parish of Orleans and

5 State of Louisiana, have invented a new and useful Improvement in Cattle-Guards, of which the following is a specification.

This invention relates to improvements in stock or cattle-guards especially designed 10 for railroads, at crossings.

The invention has for its object to provide for suitably and effectively guarding railways, particularly at crossings, against encroachment by cattle or stock, for obvious 15 reasons.

A further object is to insure the actuation of the constituent members of the guard upon the approach of the animal thereto and its contact therewith so as to halt it and 20 cause it to retreat or withdraw.

A still further object is to provide for simplifying the structure and to minimize cost of manufacture.

A still further object is to carry out the 25 aforesaid ends in an expeditious and effective manner.

The invention consists of certain instrumentalities and features substantially as hereinafter fully disclosed and defined by 30 the appended claims.

In the accompanying drawing, illustrating the preferred embodiment of my invention wherein it will be observed that various changes and modifications may be made 35 as to the detailed construction and arrangement thereof,—Figure 1 is a diagrammatical view of the invention illustrating its application to a railway track; Fig. 2 is an enlarged detailed side view of the series-connecting arrangement of the device; Fig. 3 is a detached perspective view of an individual or constituent guard member of the invention; Figs. 4 and 5 are broken detailed sectional views relating more particularly to the series-connecting arrangement and the supporting member or frame for guard-carrying shafts, respectively. Fig. 6 is a fragmentary diagrammatical view of a modification of the invention. 40 Fig. 7 is a detailed perspective view of an individual guard-member of the modification as embraced in Fig. 6.

In carrying out my invention, I suitably provide a base or frame-member 1, which is 45 triplicated or pluralized, one base or frame member being applied between the rails of

the track, and one at each side thereof, said base or frame members being suitably spiked or screwed to the ties.

Within these frame-members are arranged 50 numerous or multi-series of menacing bifurcated or forked and pointed guard-forming members 2, each series of such members being suitably secured upon an angular or rectangular shaft 3 pivotally 55 mounted in said frame-members, to allow of their being rocked as the guards are engaged by the trespassing or encroaching animal.

The rods or shafts of the lateral series of 60 guard members are preferably arranged at 70 right angles to the direction of the track or length of the rails, while the rods or shafts of the series of guard-members intermediate the rails preferably extend parallel with the 75 length of the rails. Said lateral guard-member series and said intermediate guard-member series are therefore arranged to extend parallel with the rail-lengths and at right angles thereto, respectively. The individual guard-members are preferably of 80 cast-metal, which, however, may be of sheet metal, and the salient or upstanding portions thereof 4 are bifurcated so that each salient portion is provided with two pointed 85 terminals 5 to enable the points of one guard-member to coöperate with the points of guard-members laterally thereof for 90 clasping or pricking the leg of a trespassing or encroaching animal, just above the hoof, as will be more fully disclosed later.

The guard-members 2 are also each formed with a downwardly and centrally tapered weighted bottom portion 6, to provide, by gravity, to centralize or automatically restore the guard-members to their 95 initial or upright position after the removal therefrom of previously applied pressure, as for instance, when the deterred animal backs off the guard-members. The guard-members are further provided with laterally 100 elongated portions or arms 7 in continuation of their weighted bottom portions, the arms of each series of guard-members being staggered in their arrangement with respect to each other, to insure the more effective engagement of the guard-members, as the animal places its foot thereon, the same providing for bringing the animal's foot simultaneously into contact with two or more adjacent guard members of the series.

105 The lateral and intermediate guard-series are each adapted for coaction, to provide for 110

the actuation of all the guard-members of the series when any one thereof may be engaged, which, it is apparent, will have a greater deterring effect upon the animal, in 5 attempting to cross the track, than would otherwise be the case. To that end the plurality of shafts of each series is connected together by means of similarly devised rocking members 8, one such member being 10 secured upon one end of each shaft, alternate rocking members having their arms 7 provided with curved slots 9 and lateral studs or projections 10, respectively, said studs being received by said slots for inter- 15 engagement, said studs being suitably headed in position as seen in Fig. 4.

The interconnecting arms 7 are suitably spaced against frictional or wearing contact and thus held apart by means of suitable 20 washers 11 placed upon the studs or projections 10.

This arrangement provides, as is apparent, for the rocking of any one of an entire 25 series of guard-members by delivering downward pressure upon any individual one of the guard-members as by the animal stepping thereon, as above indicated, for throwing, tilting or careening the bifurcated or pointed upstanding portions of the rocking 30 guard-members toward each other, the same thus being adapted to engage the animal's leg, just sufficiently above the hoof, to provide for pricking its leg and calling a halt of the animal and causing its retreat, 35 thus providing for effectually guarding the desired point, as will be readily appreciated.

As suggested by the modification, as embraced in Figs. 6 and 7, I may, in lieu of the form of the guard-member series as 40 above described, constitute each guard-member series substantially after the fashion of the interconnected rocking members effecting connection between each guard-member series, the same however, differentiating 45 therefrom by providing rounded shafts and

causing the guard-members to rock upon the shafts instead of fixing the guard-members upon angular shafts as in the preferred form, said rounded shafts being designated as 12. It will also be understood that, in 50 the modification, the interconnected rocking members, effecting connection between the guard-member series, are omitted.

It is thought that the foregoing description, taken in connection with the accompanying illustration, will provide for a ready understanding of the construction and operation of my invention and from which the advantages and benefits thereof may be readily appreciated, without further or extended elaboration thereof herein.

What is claimed is:—

1. A device of the type described, including a supporting frame-member, a series of shaft-supported rocking guard 65 members having upstanding pricking portions, the shafts of said guard members being supported within said supporting frame, and interconnected rocking members secured upon the shafts of said guard-members and 70 having arms adapted to be actuated by an animal stepping thereon, for causing said pricking portions to tilt or incline toward each other to engage the animal's leg.

2. A device of the type described, includ- 75 ing a series of guard-members carried by a plurality of shafts, and interconnected rocking members individually connected to said shafts, and adapted to be actuated by an animal stepping thereon, said series of 80 guard-members being equipped with means for pricking the animal's leg.

In testimony that I claim the foregoing as my own, I have hereto affixed my signature in the presence of two witnesses.

ROBERT H. F. SEWALL.
